(57) **CLAIM**

The ornamental design for a scent dispenser, as shown and described.

DESCRIPTION

FIG. 1 is a front-top perspective view of a scent dispenser showing my new design;

FIG. 2 is a front-bottom perspective view thereof;

FIG. 3 is a front elevational view thereof, wherein the rear elevational view, the left elevational view, and the right elevational view are identical thereto;

FIG. 4 is a top plan view thereof;

FIG. 5 is a bottom plan view thereof; and,

FIG. 6 is a cross sectional view taken along line 6-6 in FIG. 3.

The broken lines shown in FIGS. 1-2 and 4-6 are for illustrative purposes only and form no part of the claimed design.
